SIGNALING DEVICE

George Blair, Berwyn, Pa.

Application April 25, 1942, Serial No. 440,555

2 Claims. (Cl. 42-1)

This invention relates to signaling devices, particularly to those pyrotechnic devices used as distress signals to attract rescuers.

For many years pyrotechnic devices of various sorts have been used as distress signals to attract rescuers, particularly at sea. These have taken many forms and some of them have been generally accepted and successfully used for their designed purpose. Among those which have been popular is the "Very" pistol which is in the form of a firearm, and discharges a cartridge which sends up a luminous projectile or fire-ball. These pistols are expensive, large and heavy, as compared to my device, and for those reasons are not adapted to the use for which my device is particularly designed.

Ship sinkings at sea as the result of enemy action have occurred frequently during the past two years. In this type of sinking it has frequently been the case that lifeboats and rafts have been rendered unusable as the result of shell-fire, etc. As a result, large numbers of survivors are forced to depend solely on their lifebelts, or pieces of wreckage, etc., to keep them afloat. Such survivors have no means of navigation and must depend upon rescue by surface vessels or seaplanes.

However, in order to be rescued, these survivors must be found by the rescue vessel. This is difficult because the survivors are of such small size, compared with a lifeboat or a raft, that they cannot be easily spotted, either from surface craft or from aircraft. Very often they are visible to surface craft only for brief instants, due to waves which cut them off from view, and even though a rescue vessel may find a number of such survivors in one vicinity, there are others which have become separated from the group due to currents and tides. Many times these separated survivors have seen the rescue vessels which were searching for them, and have not been seen by the vessels, many lives being lost as a result.

Aircraft have been used to locate such survivors and to direct vessels to them. The problem here is not simplified, because due to the small size of the single survivors they are very difficult to spot from a relatively fast moving aircraft. One tried expedient has been to furnish passengers with vials of dyes which they release when they are in the water. The dyes spread over the surface and make a larger object intended to be more easily seen. This has been found to be of little assistance since the dye is dissipated quickly

and frequently is not distinguishable from the water itself, due to haze, reflection, etc.

"Very" pistols are large, cumbersome, and expensive, and it is impractical either for everyone to carry one, or to manufacture a sufficient number to furnish to everyone.

However, pyrotechnic devices are probably the most successful type of distress signals because of the fact that they are visible for great distances and because they immediately catch the eye and arrest the attention of an observer.

Accordingly, it is the major object of my invention to provide a distress signal of the pyrotechnic type that is small in size, light in weight, and easily operated. It may be made at very low cost. Compared to a "Very" pistol, which ordinarily weighs about four and one-half pounds, my device, in a size using a ten gauge size cartridge, weighs but one-half pound when loaded. Its cost is about 15% of the cost of a "Very" pistol.

It is another important object of my invention to provide a distress signal of simplified construction, of such size that several may be carried by one person without inconvenience.

It is another object of my invention to provide a distress signal which may be carried in complete safety when loaded, so that it is immediately available for use whenever needed.

Another object of my invention is the provision of a pyrotechnic type distress signal comprising a cartridge and discharge means wherein the discharge means is not much larger than the cartridge and is of such low cost that it may be discarded together with the used cartridge.

Another object of my invention is the provision of a discharge means for a pyrotechnic cartridge, wherein a closure and firing device retains the cartridge in a barrel and is operable to discharge the cartridge.

Another object of my invention is the provision of a pyrotechnic signaling device which is hand operated by pulling a firing pin against the action of a spring and releasing it to explode the pyrotechnic signal.

Another object of my invention is the provision of a pyrotechnic signaling device of small size adaptable to be carried about the person, and a safety device to prevent accidental discharge thereof.

Another object of my invention is the provision of a pyrotechnic distress signaling device which is easily operated and unaffected by submergence in water.

Further objects of the invention will appear as the description proceeds in connection with the

appended claims and the annexed drawing wherein:

Figure 1 is a side view of the complete signaling device.

Figure 2 is an end view of the device, looking toward the open end of the barrel, and with the cartridge removed.

Figure 3 is a sectional view taken in the plane 3-3 of Figure 1.

Figure 4 is a sectional view of the device, taken in the plane 4-4 of Figure 2 and showing the cartridge in place in the barrel.

Figure 5 is an end view of the device as seen from the end opposite from the open barrel end shown in Figure 2.

As best shown in Figure 4 my device comprises a holder 11 in the form of a cylindrical barrel. One end is open. The other end is enlarged as at 12 and has interior threads 13 which terminate adjacent an internal radial wall 14. The exterior wall may be knurled as at 43 and 44.

A cartridge 15 is located within the barrel. This cartridge is similar in external appearance to a shotgun shell, and may assume any conventional form. That illustrated includes side walls 16 and a metallic base 17 having a larger diameter than the rest of the cartridge to form a projecting flange 18. When inserted within the barrel of the holder 11 the flange 18 of the cartridge rests against the internal radial wall 14 of the holder.

A closure and firing device designated generally by 19 clamps the cartridge in the holder and closes the enlarged end of the holder barrel.

As best shown in Figure 4, the closure and firing device comprises a cylindrical tube 21 terminating at one end in an inwardly directed radial flange 22 having a central opening 23. At the other end of tube 21 is an exterior flange 24 which has a force fit on the tube 21. Flange 24 may be otherwise attached to tube 21 or may be integral therewith. The flange 24 has external threads 25 which engage the internal threads 13 of the holder, and the radial portion 26 of the flange clamps the flange 18 of the cartridge against the radial wall 14 of the holder.

A lug 27 may be attached or riveted to flange 24 as by a portion passing through the flange and riveted as at 28. Lug 27 provides a thumb or finger abutment which is useful when screwing the flange 24 of firing device 19 against the cartridge or when removing it by hand.

The cartridge 15 is provided with an explosive cap 29 in its base similar to the cap in a shotgun shell.

Within the cylindrical tube 21 of the closure 19 is a firing pin 31. At one end the firing pin is riveted or otherwise attached to a handle 32. At the other end, the firing pin is provided with a pointed end or striker 33, and slightly back from the striker it has an external flange 34 which may have a force fit or be integral with the firing pin 31.

A coil spring 35 surrounds the firing pin 31 and is confined between the flange 34 on the firing pin and the radial flange 22, whereby it resiliently urges the firing pin to its extreme or firing position. The firing pin is of such length that when the handle is at its extreme left position or against flange 22 the striker 33 will project beyond the radial portion 26 of the flange 24, and into the body of the explosive cap 29 of the cartridge.

When the device is loaded with an unexploded cartridge, means are provided to prevent the

striker 33 from hitting the explosive cap. This means takes the form of a device to keep the firing pin from moving to its cap-engaging position, except when it is desired to send up a signal. The device comprises a split pin 36 of resilient metal. The split pin is of such configuration that it slips over the firing pin 31 and grasps it due to the spring tension in the pin itself. As shown in Figure 5, the pin has two integral but opposed legs which resist spreading due to spring tension. The opposed legs are spread apart at their end portion and adjacent their mid-portion. When slipped over the firing pin the split pin resiliently engages the firing pin so that it will not ordinarily be dislodged. To provide a grip for pulling the split pin off from the firing pin, a chain or cord 37 is passed through the loop formed by the closed end of the split pin. The thickness of the split pin spaces the handle 32 from the flange 22 by an amount sufficient to prevent the striker 33 from hitting the cap 29 of the cartridge. When it is desired to use the signaling device, the split pin is easily removed by a quick pull on the chain 37.

The cartridge is inserted into the barrel when the closure and firing device are removed from their threaded engagement with the holder or barrel 11. In external appearance the cartridge is similar to that of the usual shotgun shell. The cartridge is charged with an explosive 38 which is ignited by the explosion of the cap 29. The explosive 38 is the propellant for the pyrotechnic composition missile shown at 39 which is advantageously sealed within the cartridge by a wall member 41. The free end of the cardboard wall of the cartridge may be turned inward to form a flange 42.

The missile 39 is a charge of pyrotechnic composition which is ignited as it leaves the cartridge and will burn with a bright light when traveling through the air, in the same manner and having the same general appearance as a fire ball from a Roman candle. A smoke producing compound may also be included in the material forming the missile. The smoke produced will generally remain in the air for a considerable time after the light has burned out.

In the case of a ten gauge cartridge, the fireball or missile will be thrown vertically about one hundred feet and will remain lighted for about three seconds. This is a sufficient length of time to catch the eye of an observer even though he may not be looking for distress signals at the time. The cartridge itself is entirely waterproofed in any desired manner, as by a paraffin seal, so that submergence in water will not affect its performance.

To discharge the cartridge to give a signal the looped cord is jerked to remove the split pin safety device. Then the barrel is pointed upwards, or in the desired direction. The handle 32 is pulled back to the dotted line position shown in Figure 4, and then quickly released. The spring 35 snaps the firing pin back and the striker 33 hits the cap 29 a hard blow to discharge the cartridge. There is substantially no recoil, and the operator grasps the barrel 11 in one hand and the handle 32 with the other when sending a signal.

The device is of such compact design, light weight, and small dimensions that a person may carry several of them without inconvenience. Since they occupy only little more room than the cartridges themselves, it is customary to load them with cartridges on board ship or at

a shore station, rather than carrying one gun and several spare cartridges as is done when the heavier and more expensive "Very" pistol is used.

Also, in view of their low cost, light weight, and compact design, it is entirely practical for every person on a ship to have one or more of the devices so that, if the ship is sunk, those surviving will each have an individual distress signal which he can use to attract rescuers. This will stop the failure to find single floating survivors who in a great many instances have been lost due to their separation from larger groups, and thus cannot be seen. A number of the devices can be carried by inflatable life rafts and by life boats. In the case of aircraft, their small size and weight makes them particularly advantageous since they will form part of the plane safety equipment which is used in the event of crash or forced landings. The signaling devices will be used to attract searchers to the scene of the crash, or to inflated rubber life boats which are used by the surviving crew members and passengers in the event of crash or forced landings at sea. My device has proved so successful in tests that a large number have been ordered by the United States Navy Department.

It is also possible to make my device in smaller sizes to use blank cartridges of twenty-two caliber size for example. It would then provide a very cheap device to replace the blank pistols used to signal the start of foot races, etc.

The invention may be embodied in other specific forms without departing from the spirit or essential characteristics thereof. The present embodiment is therefore to be considered in all respects as illustrative and not restrictive, the scope of the invention being indicated by the appended claims rather than the foregoing description, and all changes which come within the

meaning and range of equivalency of the claims are therefore intended to be embraced therein.

What is claimed and desired to be secured by United States Letters Patent is:

- 5 1. A signal shell firing device comprising a first tube adapted to receive a standard signal shell; a second tube smaller than said first tube; a firing pin and a pin actuating compression spring in said second tube, said pin projecting from the rear end of said second tube; a knob on the rear end of said firing pin for manually retracting said pin to compress said spring and for providing an abutment cooperating with the rear end of said second tube to restrain said firing pin against passing through said tube; a closure for said first tube on the end of said second tube opposite said knob; means for releasably locking said tubes together in coaxial end to end relationship with an end of said first tube 10 closed by said closure member on said second tube and the rim of a signal shell clamped between the end of said first tube and said closure; and a releasable safety stop member normally interposed between said knob and the rear end of said second tube to prevent accidental firing of said device, said stop member being manually movable to release said knob for firing said device.
- 15 2. A signal shell firing device as defined in claim 1, wherein the exterior of said first tube is roughened to provide a hand grip, the arrangement being such that said retraction of said pin preliminary to firing the device requires a manual force to be exerted on the device opposite to the force of recoil, and releasing the knob to fire the device releases said manual force to produce a recoil neutralizing condition.

GEORGE BLAIR.
